UNITED STATES PATENT OFFICE.

CHARLES SCHINDLER, OF TOLEDO, OHIO.

LIQUID SPRAYER.

Application filed May 17, 1926. Serial No. 109,458.

This invention relates to spraying devices, and particularly to those of the hand-operated type, used for spraying liquids for various purposes and embodying an air pump of the cylinder and piston type having attached thereto a receptacle for the liquid to be sprayed.

The object of the invention is the provision in connection with an instrument of this character of a simple and inexpensive form of sprayer-head, and manner of attaching to the pump, which sprayer-head by the discharge of air therethrough will effect a drawing of the liquid from the receptacle and a discharge of the liquid in fine spray form, and will also prevent the objectionable dripping of the liquid from the liquid nozzle either during use or while the instrument is at rest, a feature which is so objectionable in instruments of this type commonly used.

The invention is fully described in the following specification, and a preferred embodiment thereof illustrated in the accompanying drawings, in which—

Figure 1 is a side elevation of a device embodying the invention with a part broken away, and Fig. 2 is an enlarged central longitudinal sectional view of the spray-head and of portions of the liquid tube and the pump end with which associated.

Referring to the drawing, 1 designates a pump cylinder in which a plunger 2 operates. An operating stem or rod 3 projects from the plunger through the inner end of the cylinder 1 and carries a handle 4 at its outer end. The forward end 5 of the cylinder is closed, except for a centrally disposed opening 6 therein. A container or receptacle 7 for the liquid to be sprayed is attached in any suitable manner to the underside of the forward end portion of the cylinder.

The spray-head embodying the invention comprises an outer nozzle 8, preferably formed from sheet metal and being cylindrical in cross-section with its outer end enlarged and adapted to project through and fit into the opening 6 in the pump end 5, while its outer end is gradually restricted and provided with the discharge orifice 9. The inner end of the nozzle 8, after being projected through the opening 6, is formed with the outwardly projected radial flange 10 for engagement with the inner marginal edge wall of said opening, while the portion

of the nozzle immediately without the opening is radially expanded in annular form both to engage the outer marginal edge wall of the opening 6 in opposition to the flange 10, whereby to firmly retain the nozzle 8 against movement within said opening, and also to provide an annular recess 11 within the inner end portion of the nozzle.

The inner nozzle 12 of the sprayer-head is also preferably formed from sheet metal and is provided at its forward end with the restricted discharge orifice 13 in axial alignment with but of less diameter than the discharge orifice 9 of the nozzle 8. The nozzle 12, which may be termed the air nozzle, is flared outwardly from its forward to its inner end, so that its inner end preferably terminates in a radially projecting edge portion adapted to fit into the recess 11 of the nozzle 8. It is evident that the inner expanded edge of the nozzle 12 is placed within the inner end of the nozzle 8 before such end has been given the ogee formation shown, and that thereafter the inner end of the nozzle 8 is shaped to form the external annular groove into which the edge wall of the nozzle 12 projects.

A tube 14 for supplying liquid to the interior of the sprayer-head from the container 7 has its lower end opening into the container near its bottom and its upper end opening into the bottom portion of the nozzle 8 through a side opening therein in which the upper end of the tube, in the present instance, is shown as being fitted. It is apparent that the discharge of air from the nozzle 12 and outwardly through the orifice 9 of the nozzle 8, which discharge is effected by an operating of the plunger 2, will create a suction action within the nozzle 8 and tube 14 so as to cause a drawing of the liquid upward from the container 7 into the nozzle 8 where it is caught up by the discharging air and discharged from the nozzle 8 in finely broken up spray form. The termination of the tube 14 within the nozzle 8 prevents the liquid from dripping from the outer end of the tube 14 and running down the outer side thereof when a spraying operation is discontinued, and also which occurs when the instrument is lying idle and change in temperature conditions effects an expansion of the air and consequent pressure within the container. In the present case, liquid that may ooze from the discharge end of the tube 14 is retained

within the nozzle 8 and is discharged therefrom in atomized or spray form when the device is next operated.

It is apparent that while the inner nozzle 12 is shown as terminating a distance within the nozzle 8, it may, if desired, be extended forward a greater or less distance with respect to the discharge orifice 9, as may be desired.

10 In practice the two metal stampings forming the nozzles 8 and 12 are assembled in presses before being attached to the pump. This insures accurate spacing and aligning and prevents the parts from getting out of 15 adjustment.

It is found in practice that this form of nozzle is inexpensive in its construction and the parts thereof may be easily and quickly assembled, thereby adapting it for use in 20 connection with the inexpensive forms of spraying instruments commonly sold for household use for the spraying of liquids for the killing of flies and other insects.

I wish it understood that my invention 25 is not limited to any specific construction, arrangement or form of the parts, as it is capable of modifications and numerous changes without departing from the spirit of the claims.

30 Having thus described my invention, what I claim as new and desire to secure by Letters Patent is:

1. In an instrument of the class described, a pump end wall having an opening there- 35 in, a liquid container connected to said wall, a sprayer-head projecting from the wall,

opening and having an outer nozzle fixed in the opening and provided with an internal recess near its inner end and having a discharge orifice at its outer end, an inner nozzle having its rear end terminating in a radially projecting edge portion fitting in said recess and having its outer end terminating in a discharge orifice which is smaller than and in coaxial register with the discharge orifice of the outer nozzle, and a tube opening communication between the interior of the container and the interior of said outer nozzle.

2. In an instrument of the class described, an air pump having an end wall with an opening therein, a liquid container attached to said pump, an outer sprayer head nozzle having a discharge orifice at its forward end and having its inner end larger than said orifice with its edge wall of ogee form to provide adjacent inner and outer annular recesses, the outer recess receiving the edge wall of said pump end opening, an inner nozzle within the outer nozzle and having a radially projecting inner end edge portion fitting within the internal recess of the outer nozzle and terminating at its forward end in a discharge orifice which is in axial alignment with and restricted with respect to the discharge orifice of the outer nozzle, and a liquid supply tube leading from the interior of the container to the interior of said outer nozzle.

In testimony whereof I have hereunto 70 signed my name to this specification.

CHARLES SCHINDLER.
